United States Patent Office.

P. M. CONSUEGRA, OF NEW YORK, N. Y.

Design No. 3,537, dated June 15, 1869.

DESIGN FOR A TRADE-MARK.

The Schedule referred to in these Letters Patent and making part of the same.

To all whom it may concern:

Be it known that I, P. M. CONSUEGRA, of the city, county, and State of New York, have devised or invented a certain new and ornamental Design for a Trade-Mark for Tobacco-Paper, or for wrappers, or cases therefor, of which the following is a full and exact description.

One part of my design is an ornamental design, or picture, representing the machine known as a velocipede, without a rider. Another part, which forms a portion, or member of my distinguishing design, or trade-mark, is the word "Tobacco."

The accompanying drawing forms a part of this specification, and represents my design, of full size, which I have adopted and prefer. I propose to vary the size, however, as circumstances may render necessary, and to add the date of the patents, the name of the manufacturer, or any other words which may be found expedient.

I produce my trade-mark by the dandy-roller paper-machine, or the ordinary means of water-marking paper, but I can print it by surface, or plate-printing, lithography, or any other approved means.

Referring to the figure—

A is a wheel, with spokes, and B is another, somewhat larger. C is a connecting-frame, saddle, &c., and E F, the steering-bar, or handles. The word "Tobacco" forms a part of the same mark, or distinguishing-character, visible to the eye.

I have established a manufacture of tobacco-paper, which I have made, and intend to maintain, of a quality much superior to any before known in the market. I esteem it important to adopt some very plainly-distinguishing trade-mark, by which my goods shall be known, not only in this country, but in South America, and other countries, to which my goods are sent.

I claim as my invention, and desire to secure by Letters Patent—

The described design for a label, or trade-mark, composed of the picture, or representation of the velocipede, and the word "Tobacco," in combination, as herein set forth.

P. M. CONSUEGRA.
